DESIGN FOR A BOTTLE

Frasier Smith, Wheeling, W. Va., assignor to Hazel-Atlas Glass Company, Wheeling, W. Va., a corporation of West Virginia

Application January 16, 1937, Serial No. 67,102

Term of patent 14 years

To all whom it may concern:

Be it known that I, Frasier Smith, a citizen of the United States, residing at Wheeling, in the county of Ohio and State of West Virginia, have invented a new, original, and ornamental Design for a Bottle, of which the following is a specificcation, reference being had to the accompanying drawing forming part thereof.

Figure 1 is a side elevational view of the bottle showing my new design; and Figure 2 is an end elevational view thereof.

I claim:

The ornamental design for a bottle, as shown.

FRASIER SMITH.
